UNITED STATES PATENT OFFICE.

ROBERT BÜHLER, OF UZWIL, SWITZERLAND, ASSIGNOR TO GEBRÜDER BÜHLER, OF UZWIL, SWITZERLAND.

CLAY-WORKING MACHINERY.

SPECIFICATION forming part of Letters Patent No. 774,559, dated November 8, 1904.
Application filed April 11, 1903. Serial No. 152,213. (No model.)

To all whom it may concern:

Be it known that I, ROBERT BÜHLER, a citizen of the Republic of Switzerland, residing at Uzwil, Switzerland, have invented new and useful Improvements in Clay-Working Machinery, of which the following is a specification.

The subject of my invention is a plant for working clay, comprising a clay-cutting machine and one or more mills or crushing-rolls. The cutting-machine or pug-mill is located directly below the crushing roll or rolls, so that all the machines can be worked by a common vertical shaft carrying the rolls as well as the mixing and pressing blades of the pug-mill. By means of this arrangement the upward pressure exerted upon the vertical shaft by reason of the action of the clay-cutting machine upon the clay fed into it is more or less equalized by the downward pressure exercised by the weight of the runner-shaft, so that the bearings of the latter can be much simplified.

One construction of machinery according to my invention is illustrated in the accompanying drawings, in which—

Figure 1 shows a vertical section of the plant, having two crushing-mills; and Fig. 2, a similar view showing the pug-mill mounted directly below one of the crushing-mills.

a is the horizontal driving-shaft, mounted in two bearings and carrying the belt-pulleys *b c*. On this shaft is also keyed a bevel-wheel *d*, meshing with a second bevel-wheel *e*, keyed to the top of a vertical shaft *g*, supported by the upper bearing *f*. Concentric with the shaft *g* are the bed-plates *h* of the crushing-mills, the axes of the rolls *i* of which are connected to the vertical shaft *g* by the coupling-pieces *k*. These rolls are located around the shaft at equal angular distances apart.

Below the bed-plate *h* of the lower mill and likewise concentric with the shaft *g* is the collector-pan *l*, to the base of which is bolted the pug-mill casing *m*, the bottom of which presents a foot-step bearing *n* for the shaft *g*.

Within the pan *l* operate the rotating scrapers *o*, secured to the shaft *g*, which also carries the pugging and pressing blades *p*, in-

clined to the axis of the shaft that work within the casing of the pug-mill and protrude partly into the pan *l*. The outlet *q* of the pug-mill terminates in an exit *r*, conducting to the cutting device *s*, which may be of any suitable well-known construction. 50 55

The clay from the crushing-rolls descend through their grates into the pan *l*, where it is swept by the scrapers *o* into the pug-mill casing *m*, the blades *p* forcing it down to the exit *r*, from which it issues as a plastic bar 60 and is divided by the cutting device *s*.

The blades *p* in pugging the clay exert a lifting action on the shaft *g*, which is more or less equalized by the downward pressure due to the weight of the runner-shaft, so that 65 the step *n* and other bearings of the shaft may be of the simplest description.

Although in Fig. 1 of the drawings I have shown only a combination of a cutting-machine *p* with two crushing-mills *h k i* and a 70 collector-pan *l*, it will be obvious that the cutting-machine can be equally well used with a single crushing-mill of like description or with two crushing-mills without the collector-pan. In the latter case the pug-mill *m p* 75 should be bolted immediately to the centrally-perforated bed-plate *h'* of the lower crushing-mill *h' k' i'*, as illustrated by Fig. 2. A scraper *o'* is provided on the runner-shaft for the purpose of conducting the clay to the pug-mill, 80 as indicated at *o* in Fig. 1.

Whatever arrangement is adopted the cutting-machine constitutes the actual molding apparatus, and works up the material fed to it directly from the crushing-mills, delivering 85 it ready for being cut into bricks or the like.

Having thus described my invention, what I claim as new therein, and desire to secure by Letters Patent, is—

1. In a clay-working machine in combination, a vertical revoluble shaft, a plurality of superposed bed-plates concentric with said shaft, the lowermost bed-plate having a central aperture and a concentric imperforate track, the other bed-plates having a perforated or grated circular track in line with one another and with said imperforate track, an edge runner for each of said bed-plates, con- 90 95

nected to the shaft at equal angular distances apart, and means to discharge the clay from the lower imperforate bed-plate through the central aperture therein, for the purpose set forth.

2. In a clay-working machine in combination, a vertical revoluble shaft, a plurality of superposed bed-plates concentric with said shaft, the lowermost bed-plate having a central aperture and a concentric imperforate track the other bed-plates having a perforated or grated circular track, an edge runner for each of said bed-plates connected to the shaft at equal angular distances apart, a pug-

mill casing below the lower bed-plate, means 15 to transfer the kneaded clay from said lower bed-plate to the pug-mill casing, pug-mill blades carried by the shaft and a forming discharge-nozzle at the foot of said casing, substantially as and for the purpose set forth. 20

In testimony whereof I have signed my name to this specification in the presence of two subscribing witnesses.

ROBERT BÜHLER.
